UNITED STATES PATENT OFFICE.

JOSEPH TÖZSÉR, OF OSHAWA, ONTARIO, CANADA.

AUTOMATIC TRAIN STOP.

Application filed April 15, 1926. Serial No. 102,167.

This invention relates to certain new and useful improvements in automatic train stops and has for its primary object to provide trip devices arranged adjacent the track rails and adapted to be shifted to a position for engagement by the wheels of rolling stock passing thereover for operating a second trip device that effects operation of the air brake mechanism on the train for applying the brakes.

A further object of the invention is to provide an automatic train stop of the type above set forth wherein the trip devices arranged along the track are shifted to their operative positions for releasing the air line on the train upon the operation of electrical devices for setting a lamp signal.

With the above and other objects in view that will become apparent as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a fragmentary perspective view of a portion of a railroad track showing the trip devices for operating the air brake mechanism on the train arranged adjacent one of the track rails and the signal lamp associated with one of the trip devices,

Figure 2 is a top plan view of the track section,

Figure 3 is a vertical longitudinal sectional view through two spaced casing structures that enclose the operating mechanism for the track trip devices with the trip devices in inoperative position,

Figure 4 is a vertical longitudinal sectional view similar to Fig. 3 with one of the trip devices in its set position for operating the other trip device when depressed by a wheel of the rolling stock,

Figure 5 is a vertical longitudinal sectional view similar to Figs. 3 and 4 showing a locomotive rolling over the track trip devices,

Figure 6 is a detail view, partly in section of the trip operated releasing valve for the air brake line, and

Figure 7 is a detail sectional view of the signal lamp standard showing the connection between the journaled shaft support

ing the signal lamp and one of the track trip devices.

As shown in Figures 1 and 2, the track rails 10 and 11 are supported on the cross ties 12 with a movably mounted trip plate 13 disposed adjacent the outer side of the rail 10 to be engaged by the front wheel 14 of the locomotive 15 and having operative connections with the trip plate 16 movably mounted at a point inwardly of the rail 10 to engage the plunger rod 17 shown in Fig. 6 for releasing a valve in the air brake line 18 for the automatic application of the wheel brakes. The signal lamp 19 is rotatably supported in the casing stand 20 is operatively connected to the track trip 13 for automatically raising the trip 13 to its operative set position when the signal lamp 19 is moved to its stop position, the lamp being electrically shifted through the medium of the wiring illustrated in Fig. 1 in any appropriate manner and as a further warning to the engineer of the train, the semaphore 21 upon the post 22 may be simultaneously shifted to its horizontal stop position.

The track trip 13 is associated with operating mechanism therefor housed within the casing 23 shown more clearly in Figures 3 to 5 as being disposed beneath the track rail 10, a lug 24 depending from one end of the trip 13 and pivotally supported at its lower end upon the bracket 25. The pin 26 depending from the forward curved end 13^a of the trip 13 slides through a guide block 27. The operating mechanism for the trip 13 further includes a standard 28 supported upon the bottom wall of the casing 23 and upon the upper end of which a lever 29 is pivotally supported intermediate its ends. As shown in Fig. 7, the signal lamp 19 is carried by the vertical shaft 30 that is journaled in the casing stand 20 and has a bevel gear connection 31 at its lower end with the shaft 32 extending through a side wall of the casing stand 20 and entering the casing 23 as shown in Figs. 3 and 4. A lever 33 fixed at one end to the shaft 32 has a link connection 34 with one end of the lever 29.

A disk wheel 35 is rotatably supported in the casing upon the bearings 36 and carries a laterally projecting pin 37 adjacent its peripheral edge that is received in the slotted end 38 of the link 39 that is pivotally at-

tached to the other end of the lever 29. The connection between the track trip 13 and the disk wheel 35 includes a link 40 anchored at one end as at 41 to the peripheral edge of the disk wheel 35 while its other upper end is pivotally attached to the lug 42 depending from the track trip 13 as shown in Figs. 3 and 4. With the elements in the position shown in Fig. 3, the link 39 is at its limit of downward movement with the pin 37 carried by the disk wheel 35 disposed in the lower end of the closed slot 38 while the track trip 13 is disposed in horizontal alinement with the track rail 10. When the signal lamp 19 is shifted to stop position, rotation of the shaft 30 is communicated to the shaft 32 and through the arm and link connection 33 and 34 with the lever 29, the latter is operated to elevate the link 39 to partially rotate the disk wheel 35 for elevating the track trip 13 to the position shown in Fig. 4 through the medium of the link connection 40 between the disk wheel and the track trip and when so disposed the point of connection 41 between the link 40 and the disk wheel is disposed at the opposite side of the vertical axis of the disk wheel.

Devices are interposed between the track trip 13 and the trip 16 that operates the plunger rod 17 of the air release valve for elevating the forward end of the trip 16 when the forward elevated end of the track trip 13 is depressed. These devices and the mounting for the trip 16 include a casing 43 supported upon one of the cross ties 12 inwardly of the track rail 10 and having a bracket 44 extending upwardly therefrom upon the upper end of which the rear end of the trip 16 is pivotally mounted as at 45. A pair of sprocket wheels 46 and 47 journaled in the casing 43 are traversed by a sprocket chain 48 while a link arm 49 extends between the sprocket wheel 47 and the forward end of the trip 16. The bracket 50 mounted in the casing 43 adjacent the disk wheel 35 has a bell crank lever pivotally supported thereon as at 51, the leg 52 of the bell crank lever having a rod connection 53 with the sprocket wheel 46 in the casing 43. The other leg 54 of the bell crank lever carries an end abutment 55 with a coil spring 56 interposed between the end abutment and the bracket 50 for normally retaining the same in an elevated position. An arm 57 radially projecting from the periphery of the disk wheel 35 carries a knob 58 upon one side thereof at its outer end that is received in the centering socket 59 in the abutment 55. With the track trip 13 in its elevated set position as shown in Fig. 4 the wheel 14 of the locomotive 15 in passing thereover depresses the same for causing the arm 57 to depress the abutment 55 against the tension of the spring 56 and operates the bell crank lever and causes rotation of the sprocket

wheels 46 and 47 to elevate the forward end of the trip 16 through the medium of the link connection 49 between the sprocket wheel 47 and said trip. When the track trip 13 is depressed as shown in Fig. 5 the pin 37 carried by the disk wheel moves upwardly in the slotted end 38 of the link 39 without operating the link, and, of course, does not disturb the signal lamp 19 when in its stop signalling position.

With the forward end of the trip 16 elevated as shown in Fig. 5 the same is positioned for engagement with the head 60 upon the lower end of the plunger rod 17 that works in the guide 61 as shown in Fig. 6. The laterally disposed elbow 62 carried by the plunger rod 17 engages the stem 63 of the valve 64 that is spring pressed as at 65 and is disposed in the air line pipe 18 for elevating the valve 64 from its seat to permit the escape of air through the passages 66 and the application of the air brakes to the locomotive wheels. It will, therefore, be observed that should the engineer fail to follow the stop instructions of the signal lamp 19 and semaphore 21, the operation of the track trip 13 will elevate the trip 16 for the automatic operation of the air brake line 18 for the application of the air brakes upon the train wheels. When the locomotive wheels 14 pass over the track trip 13, the same is elevated to the position shown in Fig. 4 by the spring 56 which also lowers the forward end of the trip 16 and disposes the pin 37 upon the disk wheel 35 at the lower end of the slot 38 in the link 39. When the signal lamp 19 is shifted to its open or go position, rotation of the shaft 30 caused by movement of the shaft 32 carrying the signal lamps 19 will operate the lever 29 to lower the link 39 and shift the pivotal connection 41 between the link 42 in the track trip 13 to the opposite side of the vertical axis of the disk wheel 35 and at which time the weight of the track trip will cause further rotation of the disk wheel 35 and during lowering movement of the track trip and rotation of said wheel the pin 37 is again positioned at the lower end of slot 38 in the link 39. The signal lamp 19 may be operated in any manner desired, either electrically, manually or mechanically.

While there is herein shown and described the preferred embodiment of the present invention, it is, nevertheless to be understood that minor changes may be made therein without departing from the spirit and scope of the invention as claimed.

What is claimed is:—

1. In an automatic train stop, a pair of track trips, one of said trips being operated by the wheels of rolling stock, an air line valve operated rod engaged by the other trip, operative connections between the two trips, both of said trips being pivotally mounted,

the connections between the two trips including rotatable members having link connections with the free ends of the trips, tensioned lever and link devices connected to the rotatable member associated with the trip that engages the valve operating rod and an arm projecting radially from the rotatable member associated with the wheel operated trip and movable into engagement with the tensioned lever and link devices for operating the latter when the wheels of rolling stock pass over the last named trip.

2. In an automatic train stop, a pair of track trips, one of said trips being operated by the wheels of rolling stock, an air line valve operating rod engaged by the other trip, connections between the trips to cause movement of the valve operating trip to its set position upon operative depression of the wheel operated trip, both of said trips being pivotally mounted, the connections between the two trips including rotatable members having link connections with the free ends of the trips, tensioned lever and link devices connected to the rotatable member associated with the trip that engages the valve operating rod, and an arm projecting radially from the rotatable member associated with the wheel operated trip and movable into engagement with the tensioned lever and link devices for operating the latter when the wheels of rolling stock pass over the last named trip.

3. In an automatic train stop, a pair of track trips, one of said trips being operated by the wheels of rolling stock, an air line valve operating rod engaged by the other trip, operative connections between the two trips, a stop signal lamp operatively connected to the wheel operated trip for moving the same to its operative position when the lamp is moved to stop position, both of said trips being pivotally mounted, the connections between the two trips including rotatable members having link connections with the free ends of the trips, tensioned lever and link devices connected to the rotatable member associated with the trip that engages the valve operating rod and an arm projecting radially from the rotatable member associated with the wheel operated trip and movable into engagement with the tensioned lever and link devices for operating the latter when the wheels of rolling stock pass over the last named trip.

4. In an automatic train stop, a pair of track trips, one of said trips being operated by the wheels of rolling stock, an air line valve operating rod engaged by the other trip, connections between the trips to cause movement of the valve operating trip to its set position upon operative depression of the wheel operated trip, a stop signal lamp op-

eratively connected to the wheel operated trip for moving the same to its operative position when the lamp is moved to stop position, both of said trips being pivotally mounted, the connections between the two trips including rotatable members having link connections with the free ends of the trips, tensioned lever and link devices connected to the rotatable member associated with the trip that engages the valve operating rod, and an arm projecting radially from the rotatable member associated with the wheel operated trip and movable into engagement with the tensioned lever and link devices for operating the latter when the wheels of rolling stock pass over the last named trip.

5. In an automatic train stop, a pair of track trips, one of said trips being operated by the wheels of rolling stock, an air line valve operated rod engaged by the other trip, operative connections between the two trips, both of said trips being pivotally mounted, the connections between the two trips including rotatable members having link connections with the free ends of the trips, tensioned lever and link devices connected to the rotatable member associated with the trip that engages the valve operating rod, an arm projecting radially from the rotatable member associated with the wheel operated trip and movable into engagement with the tensioned lever and link devices for operating the latter when the wheels of rolling stock pass over the last named trip, the tensioned lever and link devices comprising a bracket, a bell crank lever supported on the bracket, a spring interposed between the bracket and the end of one leg of the lever, a rod connecting the other lever leg to the rotatable member associated with the trip for the valve operating rod and the arm on the rotatable member being movable into engagement with the spring pressed end of the bell crank lever.

6. In an automatic train stop, a pair of track trips, one of said trips being operated by the wheels of rolling stock, an air line valve operating rod engaged by the other trip, connections between the trips to cause movement of the valve operating trip to its set position upon operative depression of the wheel operated trip, both of said trips being pivotally mounted, the connections between the two trips including rotatable members having link connections with the free ends of the trips, tensioned lever and link devices connected to the rotatable member associated with the trip that engages the valve operating rod, an arm projecting radially from the rotatable member associated with the wheel operated trip and movable into engagement with the tensioned lever and link devices for operating the latter when the wheels of rolling stock pass over the last named trip.

4
named trip, the tensioned lever and link devices comprising a bracket, a bell crank lever supported on the bracket, a spring interposed between the bracket and the end of 5 one leg of the lever, a rod connecting the other lever leg to the rotatable member associated with the trip for the valve operating rod and the arm on the rotatable member being movable into engagement with the spring 10 pressed end of the bell crank lever.

7. In an automatic train stop, a pair of track trips, one of said trips being operated by the wheels of rolling stock, an air line valve operating rod engaged by the other 15 trip, operative connections between the two trips, a stop signal lamp operatively connected to the wheel operated trip for moving the same to its operative position when the lamp is moved to stop position, both of 20 said trips being pivotally mounted, the connections between the two trips including rotatable members having link connections with the free ends of the trips, tensioned lever and link devices connected to the rotatable member associated with the trip that engages the valve operating rod, an arm projecting radially from the rotatable member associated with the wheel operated trip and movable into engagement with the tensioned lever and link devices for operating the latter when the wheels of rolling stock 25 pass over the last named trip, the tensioned lever and link devices comprising a bracket, a bell crank lever supported on the bracket, a spring interposed between the bracket and the end of one leg of the lever, a rod connecting the other lever leg to the rotatable member associated with the trip for the valve operating rod and the arm 30

on the rotatable member being movable into 40 engagement with the spring pressed end of the bell crank lever.

8. In an automatic train stop, a pair of track trips, one of said trips being operated by the wheels of rolling stock, an air line 45 valve operating rod engaged by the other trip, connections between the trips to cause movement of the valve operating trip to its set position upon operative depression of the wheel operated trip, a stop signal 50 lamp operatively connected to the wheel operated trip for moving the same to its operative position when the lamp is moved to stop position, both of said trips being pivotally mounted, the connections between the 55 two trips including rotatable members having link connections with the free ends of the trips, tensioned lever and link devices connected to the rotatable member associated with the trip that engages the valve operating rod, an arm projecting radially from the rotatable member associated with the wheel operated trip and movable into engagement with the tensioned lever and link devices for operating the latter when the 60 wheels of rolling stock pass over the last named trip, the tensioned lever and link devices comprising a bracket, a bell crank lever supported on the bracket, a spring interposed between the bracket and the end of 65 one leg of the lever, a rod connecting the other lever leg to the rotatable member associated with the trip for the valve operating rod and the arm on the rotatable member being movable into engagement with the 70 spring pressed end of the bell crank lever.

In testimony whereof I affix my signature.
JOSEPH TÖZSÉR.
